UNITED STATES PATENT OFFICE

104,380

DESIGN FOR A RACK FOR BEER-FOAM SCRAPERS

Louis Poglein, Jeannette, Pa., assignor to McKee
Glass Company, Jeannette, Pa., a corporation of Pennsylvania

Application December 11, 1936, Serial No. 66,472

Term of patent 14 years

To all whom it may concern:

Be it known that I, Louis Poglein, a citizen of the United States, residing at Jeannette, in the county of Westmoreland and State of Pennsylvania, have invented a new, original, and ornamental Design for a Rack for Beer-Foam Scrapers, of which the following is a specification, forming part thereof, in which Figure 1 is a rear elevational view; and Figure 2 a side elevational view of a rack for beer-foam scrapers showing my new design.

I claim:

The ornamental design for a rack for beer-foam scrapers as shown.

LOUIS POGLINE.
